RUDOLPH KLEIN, OF NEW YORK, N. Y., ASSIGNOR OF ONE-FIFTH TO
BYRON G. HARLAN, OF ORANGE, NEW JERSEY.

DISK-TALKING-MACHINE BLANK.

No. 814,053.

Specification of Letters Patent.

Patented March 6, 1906.

Application filed March 19, 1904. Serial No. 198,909.

To all whom it may concern:

Be it known that I, RUDOLPH KLEIN, a citizen of the United States, residing at New York city, county and State of New York, have invented a new and useful Improvement in Disk-Talking-Machine Blanks, of which the following is a specification.

The object of my invention is to provide a ready means of producing disk-talking-machine records of a wax composition or the like in such a manner as to enable said records to be utilized in connection with the usual apparatus employed for reproducing the permanent records of trade and at the same time protect such records from accidental injury through being scratched or rubbed together. My device also secures the ready tracking of the recording-stylus in making said sound-records on my improved blanks, resulting in the sound-record being made in the form of a volute spiral on the disk. I attain these objects by the means illustrated in the accompanying drawings, which form part of this specification, and in which—

Figure 1 shows a top or plan view of one form of my improved device. Fig. 2 shows a cross-section on line G H of Fig. 1.

Fig. 1 shows a disk A with two volute spirals C and D thereon parallel with each other, one of said spirals C being filled with

a wax composition or the like. Same figure, B shows a hole in center of said plate or disk.

The operation or use of my improved disk is as follows: The disk A, Fig. 1, is placed on the turn-table of what is known as a "disk talking-machine," and the stylus of the recording device is placed upon the volute curve C, while an arm, carrying a pointed end bent down into the parallel spiral or volute D, aids in keeping the recording device true in track C. 35 40

What I claim as my invention, and desire to secure by Letters Patent, is—

1. In a disk-blank for talking-machines, a rigid disk with multiple parallel volute spirals thereon, one of which spirals shall have therein a wax-like-record composition or material. 45
2. In a disk-blank for talking-machines, a rigid disk with multiple parallel volute spirals thereon, all but one of said volute spirals having therein a wax-like composition or record material. 50

In testimony whereof I have signed my name to this specification, in the presence of two subscribing witnesses, this 11th day of March, 1904. 55

RUDOLPH KLEIN.
